UNITED STATES PATENT OFFICE.

ROBERT CAIRNS AND JOSEPH W. CAIRNS, OF WATERTOWN, WISCONSIN.

COIN-DELIVERY MACHINE.

Application filed April 22, 1922. Serial No. 556,028.

To all whom it may concern:

Be it known that we, ROBERT CAIRNS and JOSEPH W. CAIRNS, citizens of the United States, residing at Watertown, in the county 5 of Jefferson and State of Wisconsin, have invented new and useful Improvements in Coin-Delivery Machines, of which the following is a specification.

This invention relates to change-making 10 and other coin-delivery machines, and its object is to provide a machine of this kind in which the coin-ejecting mechanism is power-operated, the power source being an electric motor. The machine is controlled 15 by a series of manually operated keys by means of which a selector mechanism is operated to effect the ejection of the coins required to make up the sum of money to be thrown out, and these keys also operate to 20 throw a switch which closes the energizing circuit of the motor, and to control a clutch by which the motor is connected to a shaft carrying actuators for the coin-ejector mechanism. The machine also embodies 25 other novel and improved mechanism whereby the entire operation of ejecting the selected coin or coins is automatically effected after depressing the proper key, the parts being all restored to inoperative position 30 after each operation. A safety device is also provided for preventing damage to the mechanism if the coin ejectors should meet with an obstruction, and the actuating means of the ejectors are adjustable to im- 35 part to the latter a working stroke of the proper length.

Other novel and improved details of construction and modes of operation will be pointed out in the description appearing 40 hereinafter.

In order that the invention may be better understood, reference is had to the accompanying drawings, wherein:

Figure 1 is an end view of the apparatus; 45 Fig. 2 is a cross-section; Fig. 3 is a plan view with a portion of a casing broken away; Fig. 4 is a section on the line 4—4 of Fig. 3; Fig. 5 is an enlarged side elevation of one of the units of a selector mechanism; 50 Fig. 6 is a view similar to Fig. 5 showing the parts in another position, and Fig. 7 is an enlarged elevation of a detent and other parts associated with a switch mechanism.

Referring specifically to the drawings, the machine is provided with a plurality of 55 coin chutes 10 designed to support stacks of coins of various denominations. With each coin chute is associated an ejector finger 11 for pushing the bottom coin from beneath the stack. Each ejector 11 is carried 60 by a slide block 12 mounted on a guide stem 13, and connected by a link 14 to one end of a lever 15 pivoted at its other end, as shown at 16, to a suitable support 17. The lever 15 has a laterally extending arm 65 18 which is connected at its outer end by a link 19 to a collar 20 carried by a vertically reciprocatory stem 21. The collar 20 is loose on the stem 21, and on the latter are 70 fixed abutments 22 and 23. Between the upper abutment 22 and the top of the collar 20 is a spring 24, the same being coiled around the stem 21 and tending to hold the collar down against the lower abutment 23. This construction provides a yieldable connection 75 between the stem 21 and the collar 20. The ejector finger 11 is given a forward or working stroke when the stem 21 is drawn downwardly, this motion of the stem being communicated to the collar 20 80 by the abutment 22 and the spring 24, and the downward movement of the collar 20, through the link 19 and lever arm 18, causes the lever 15 to swing in a direction to advance the slide block 12 to give the finger 11 85 its ejecting stroke. If the finger 11 should meet an obstruction, such as a bent coin, no damage will be done to any parts of the mechanism, as the collar 20 is loose on the stem 21, and the blocking of the finger 11 90 will merely result in the collar 20 remaining stationary as the stem 21 continues to go down.

The lower end of the stem 21 carries a support 25 for a slidable finger 26, the same 95 extending laterally from the stem, and being adjustable to intercept a wiper member carried by a power-driven shaft 27. This wiper consists of a radial arm 28 made fast on the shaft 27 and having adjustably fastened to its outer end a blade 29. When the blade 29 strikes the finger 26, the stem 21 is drawn down to give the finger 11 an ejecting stroke as hereinbefore described, and the length of this stroke can be very accurately adjusted according to the diameter 100 105

of the coins by advancing or retracting the blade 29. The adjustable connection between the blade 29 and the member 28 may be made by a screw 30 passing into the latter through a longitudinal slot 31 in the former. The finger 26 is normally in retracted position out of the path of the blade 29, and it is so held by a spring 32.

The stem 21 is supported by a pair of vertically spaced plates 33 and 34 having aligned apertures in which the stem slidably seats. A spring 35, anchored to the upper plate 33 and connected to the support 25, tends to hold the stem normally elevated, and after the downward working stroke of the stem, the spring restores it to elevated position.

An ejector mechanism as hereinbefore described is provided for each coin chute 10, and in order to select the ejector unit which will throw out the desired coin or coins, the machine is provided with a bank of depressible keys 36, each having its stem 37 fitted at the bottom with one or more lugs 38 adapted to engage a corresponding member of yoke bars 39 pivoted at their ends, as shown at 40, to suitable supports 41. Beneath each yoke bar 39 is located a vertically positioned and slidable stem 42, the upper end of said stem having a head 43 which is pressed by the yoke bar when the latter is rocked by a finger 38 as the key stem 37 is pushed down. Each key stem 37 has a restoring spring 44, and each stem 42 has a restoring spring 45 positioned between an abutment 46 on the stem and a bottom guide 47 in which the stem works, said guide being carried by the plate 34. The plate 33 also carries a guide 48 for the stem 42.

A stem 42 is associated with each stem 21, the purpose of the former being to advance the finger 26 so that it may intercept the wiper blade 29 as hereinbefore described. In order that the stem 42 may function in this manner, its lower end is connected by a link 49 to a lever 50 fulcrumed at 51 to a depending bracket 52 carried by the plate 34. This bracket also supports an angle lever, one branch 53 of which is pivoted to the bracket at 52^a, whereas its other branch 54 is located at its extremity behind a side lug 55 on the forward end of the finger 26. At the junction of the two branches 53 and 54 of the angle lever is a side pin or abutment 56 which rests on the lever 50. It will be evident from the foregoing that the downward movement of the stem 42 causes the rear portion of the lever 50 to swing upwardly, and through the abutment 56 to tilt the angle lever in such a direction that the branch 54 of the latter pushes against the lug 55 and advances the finger 26 to come into the path of the wiper blade 29 as shown in Fig. 6. In order to hold the finger advanced, the bracket 52 carries a latch hook 57 which drops into a keeper notch 58 in the

top edge of the finger 26 when the latter is advanced as described. When the wiper blade 29 engages the advanced finger 26, the stem 21 is drawn down to effect the operation of the ejector finger 11, and as the finger 26 now moves away from the latch 57, said finger is released so that it may be retracted by the spring 32 when the blade 29 clears the finger. It will also be understood that the parts 37, 38, 39, 42, 50, 53 and 54 are restored to their normal position when the key 36 is released.

The drawings illustrate only one of the ejector units, it being understood that the construction and operation of the entire set of units is the same. Fig. 4 shows one of the key stems 37 equipped with a single lug 38 for operating the stem 42 of a single unit, and a second key stem having two lugs for operating the stems 42 of two different units. The machine is provided with nine coin chutes 10, with a coin ejector unit for each chute. The chutes are designed to hold dollars, half-dollars, quarters, dimes, nickles and pennies, two dime chutes, two nickle chutes and two penny chutes being provided. One hundred and one keys 36 are provided, and the selector mechanism is arranged so that any amount of change up to a dollar may be made by pressing one key.

The driving means for the shaft 27 is an electric motor 59 having its shaft 60 equipped with a worm 61 which is in mesh with a worm-wheel 62 loose on the shaft 27. In order to establish a driving connection between the worm-wheel 62 and the shaft 27, there is mounted on said shaft a clutch member 63 having its jaws adapted to engage clutch jaws 64 on the worm-wheel. The clutch member 63 is splined or otherwise connected to the shaft 27 so as to turn therewith and also be free to slide thereon. To a base board 65 supporting the motor 59 is pivoted, as shown at 65^a, a clutch shifter fork 66 straddling the clutch member 63 and seating in a circumferential groove 67 therein. The end of the shaft 27 adjacent to the clutch member 63 is fitted with a wiper 68, and between the latter and the clutch member is a coiled spring 69 having a function to be presently described. The clutch member 63 is held normally disengaged from the clutch jaws 64 by a detent 70 engaging the free end of the shifter fork 66. The detent 70 is pivoted, as shown at 71, to a rocker arm 71^a on a rock shaft 72 journaled at one end in a bearing 73 carried by the base board 65, and at its other end in a bearing 74 carried by a bracket 75. To the detent 70 is connected a spring 76 which is anchored to the bracket 75 and tends to hold the detent down in engagement with the shifter fork 66. When the detent 70 is tripped off the shifter fork 66, the

latter is swung by a spring 77 in a direction to slide the clutch member 63 over into engagement with the clutch jaws 64 of the worm-wheel 62. The spring 77 is connected 5 to the free end of the fork 66.

From one side of the detent 70 projects a pin 78 beneath which is located one end of a trip lever 79 fulcrumed to a support 80 on the bracket 75. The other end of 10 the lever 79 is located beneath a foot piece 81 on the bottom of a vertically slid able stem 81^a supported in guides 82 carried by an upright support 83, which latter also carries bearings 83^a in which the shaft 60 is 15 journaled. Extending transversely of the series of yoke bars 39 and beneath the same, is a pivoted yoke bar 84 which is swung whenever the bars 39 are actuated by the key stems 37 as hereinbefore described. 20 The bar 84 is supported by frame members 85, and it is held up against the bars 39 by springs 86 connected to its ends. To one end of the bar 84 is fastened a laterally extending finger 87 which is so positioned 25 that it bears down against the upper end of the stem 81^a to push the same downwardly when the bar 84 is depressed. This downward movement of the stem 81^a swings the trip lever 79 in a direction to trip the 30 detent 70 off the clutch-shifter fork 66, thereby releasing said fork and permitting the spring 77 to slide the clutch member 63 over into engagement with the clutch jaws 64 of the worm-wheel 62, to couple the latter to the shaft 27. The lever 79 is 35 provided with a return spring 79^a connected to its rear end and anchored to the bracket 75.

To the rock-shaft 72 is fastened a laterally extending arm 88 to the outer end of which is connected a coiled spring 89 anchored to a frame part 90. On the shaft 72 is also fastened a laterally extending arm 91 which is in the path of the wiper 68. 40 After the shaft 27 has been coupled to the worm-wheel 62 as hereinbefore described, and made one complete revolution, the clutch member 63 is retracted to break the driving connection, this being effected by the wiper 68 now engaging the arm 91 and thereby rocking the shaft 72 in a direction to advance the detent 70 and reengage it with the fork 66, this movement of the shaft 72 being opposed by the spring 89. When 45 the wiper 68 slips off the arm 91, the shaft 72 is released, whereupon it is rocked by the pull of the spring 89 on the arm 88, in a direction to withdraw the clutch member 63 from the clutch teeth 64 of the worm-wheel 62, this action being effected by the 50 detent 70 which is now engaging the fork 66 and is drawn back by the rocker arm 71^a to which it is connected, said rocker arm swinging as the shaft 72 is rocked. When 55 the clutch member 63 is drawn back as de-

scribed, the spring 69 is compressed so that it operates as a brake to bring the shaft 27 to a quick stop.

The switch mechanism which controls the circuit of the motor 59 is best shown in 70 Figs. 1 and 7. A base plate 92 of insulating material carries a stationary switch contact 93 to which one side of the circuit is connected through a fuse 94. The other side of the circuit is connected to a movable contact 95 carried by a strip 96 of insulating material, which latter, in turn, is carried by one of the arms 97 of an angle lever fulcrumed at 98 to a suitable support 99, the other arm of said lever being shown at 01, 80 and extending into the path of a wiper 02 on the shaft 27 when the lever has swung to bring the contact 95 into engagement with the contact 93. The contact 95 is normally free of the contact 93 and it is so held by 85 the angle lever being held by a detent 03 pivoted at 04 to a support 05. A spring 06 connected to the lever arm 97 swings the angle lever in a direction to engage the contact 95 with the contact 93 when the detent 03 releases said lever, whereupon the 90 circuit of the motor 59 is closed. A guide 07 is provided for the free end of the lever arm 97.

The detent 03 is tripped off the lever arm 95 95 every time any one of the key stems 37 is operated. As pointed out hereinbefore, the depression of a key stem 37 rocks the yoke bar 84, and hence in order to effect the tripping of the detent when the 100 key stem is pushed down, the bar 84 is provided with a depending stem 07 which is positioned to engage an arm 08 extending laterally from the detent 03. A spring 09 connected to the detent 03 tends to hold 105 it normally in engagement with the lever arm 97, and to bring it into engagement therewith when said lever arm is swung to disengage the contact 95 from the contact 93.

The operation of the machine may be 110 summarized as follows:

The operator presses down the key 36 which denotes the amount of money to be ejected. The key is held depressed only momentarily, and may then be released. This 115 operation selects the proper ejector mechanism, closes the circuit of the motor 59, and also couples the shaft 27 to the motor through the clutch mechanism hereinbefore described. The shaft 27 is thus set in motion, and when the blade 29 strikes the advanced finger 26 as shown in Fig. 6, the ejector mechanism is operated, and immediately thereafter the wiper 02 strikes the lever arm 01 to swing said arm 97 in a direction to carry the contact 95 away from the contact 93 and thus break the motor circuit. At the same time, the clutch member 63 is disengaged to break the driving connection between the motor 59 and the shaft 120 125 130

27, so that the latter comes to a stop, and all the parts have now resumed their normal position, and are reset for the next operation.

- 5 5. Suitable supporting frames will be provided for the various parts of the mechanism hereinbefore described, and the apparatus is also provided with a casing in which the mechanism is housed, and as these are 10 immaterial to the invention they have not been described in detail. One end of the casing is provided with an opening which exposes the switch mechanism, and this opening is provided with a door 00 which is 15 shown swung open in Fig. 1.

We claim:

1. In a coin-delivery machine, coin-ejectors, means for operating the ejectors, a power-driven shaft, slidable means for selectively establishing an actuating connection between the shaft and the ejector-operating means, keys controlling said selective connecting means, and means actuated by the keys for controlling the shaft.

2. In a coin-delivery machine, coin-ejectors, means for operating the ejectors, a shaft, an electric motor, a switch controlling the motor circuit, a clutch for establishing a driving connection between the motor and the shaft, slidable means for selectively establishing an actuating connection between the shaft and the ejector-operating means, keys controlling said selective connecting means, and means actuated by the keys for controlling the aforesaid clutch and switch.

3. In a coin-delivery machine, coin-ejectors, means for operating the ejectors, a power-driven shaft, actuators on the shaft for the ejector-operating means, said ejector-operating means having slidable actuating means movable into and out of operative relation with respect to the aforesaid actuators, means for shifting said actuating means into operative position, selectors for said shifting means, keys for operating the selectors, and means actuated by the keys for controlling the aforesaid shaft.

4. In a coin-delivery machine, coin-ejectors, means for operating the ejectors, a shaft, an electric motor, a clutch for establishing a driving connection between the motor and the shaft, a switch controlling the motor circuit, actuators on the shaft for the ejector-operating means, said operating means having actuating means movable longitudinally into and out of operative relation with respect to the actuators, means for shifting said actuating means into operative position, selectors for said shifting means, keys for operating the selectors, and means actuated by the keys for controlling the aforesaid clutch and switch.

5. In a coin-delivery machine, coin-ejectors, an operating means for each ejector, each of said means including a slidably sup-

ported stem, and an actuator member carried by said stem and movable laterally thereof into and out of operative position, selectors for the actuator members, keys for operating the selectors, a power-driven shaft 70 having wipers adapted to engage the actuator members when in operative position, and means actuated by the keys for controlling the shaft.

6. In a coin-delivery machine, coin-ejectors, an operating means for each ejector, each of said means including a slidably supported stem and an actuator member carried by said stem and movable laterally thereof into and out of operative position, 75 a support, levers carried by the support and engageable with the actuator members, other levers carried by the support and engageable with the first-mentioned levers for operating the same, slidable stems operatively connected to the second levers, selectors for the last-mentioned stems, keys for operating the selectors, a power-driven shaft having wipers adapted to engage the actuator members 80 when in operative position, and means actuated by the keys for controlling the shaft.

7. In a coin-delivery machine, coin-ejectors, an operating means for each ejector, each of said means including a slidably supported stem, and an actuator member carried by said stem and movable laterally thereof into and out of operative position, 95 selectors for the actuator members, keys for operating the selectors, a power-driven shaft having wipers adapted to engage the actuator members when in operative position, latches engageable with the actuator members for holding the same in operative position, said latches releasing the actuator members 100 after each operation, means for retracting the actuator members when thus released, and means actuated by the keys for controlling the shaft.

8. In a coin-delivery machine, coin-ejectors, an operating means for each ejector, each of said means including a slidably supported stem and an actuator member carried by said stem and movable laterally thereof into and out of operative position, a support, levers carried by the support and engageable with the actuator members, other levers carried by the support and engageable with the first-mentioned levers for operating the same, slidable stems operatively connected to the second levers, selectors for the last-mentioned stems, keys for operating the selectors, a power-driven shaft having wipers adapted to engage the actuator members 115 when in operative position, latches engageable with the actuator members for holding the same in operative position, said latches releasing the actuator members after each operation, means for retracting the actuator members when thus released, and 120 means actuated by the keys for controlling the shaft.

65 9. In a coin-delivery machine, coin-ejectors, an operating means for each ejector, each of said means including a slidably sup-

means actuated by the keys for controlling the shaft.

9. In a coin-delivery machine, coin-ejectors, means for operating the ejectors, a power-driven shaft, a clutch controlling the shaft, means for selectively establishing an actuating connection between the shaft and the ejector-operating means, keys controlling said selective connecting means, a clutch shifter member, a detent for holding said member in clutch-disengaging position, means for shifting said member to clutch-engaging position when the detent is tripped, a lever for tripping the detent, means actuated by the keys for operating the lever, means for re-engaging the detent with the shifter member, and means for thereafter moving the shifter member to disengage the clutch.

10. In a coin-delivery machine, coin-ejectors, means for operating the ejectors, a power-driven shaft, a clutch controlling the shaft, means for selectively establishing an actuating connection between the shaft and the ejector-operating means, keys controlling said selective connecting means, a clutch shifter member, a detent for holding said member in clutch-disengaging position, means for shifting said member to clutch-engaging position when the detent is tripped, a lever for tripping the detent, means actuated by the keys for operating the lever, means for re-engaging the detent with the shifter member, means for thereafter moving the shifter member to disengage the clutch, and means for checking the movement of the shaft after such disengagement of the clutch.

11. In a coin-delivery machine, coin-ejectors, means for operating the ejectors, a power-driven shaft, a clutch controlling the shaft, means for selectively establishing an actuating connection between the shaft and the ejector-operating means, keys controlling said selective connecting means, a clutch shifter member, a detent for holding said member in clutch-disengaging position, means for shifting said member to clutch-engaging position when the detent is tripped, a lever for tripping the detent, means actuated by the keys for operating the lever, a rock-shaft, an arm extending from said shaft and carrying the detent, a second arm extending from the rock-shaft, a wiper on the first-mentioned shaft and engageable with the second arm for operating the rock-shaft in a direction to re-engage the detent with the shifter member, and means for thereafter operating the rock-shaft in a direction to move the shifter member through the detent to clutch disengaging position.

12. In a coin-delivery machine, coin-ejectors, means for operating the ejectors, a shaft, means for selectively establishing an

actuating connection between the shaft and the ejector-operating means, keys controlling said selective connecting means, an electric motor driving the shaft, a switch controlling the motor circuit, said switch consisting of a stationary and a movable member, a pivoted support for the movable switch member, a detent for holding said support, means for swinging the support to engage its switch member with the stationary switch member when the detent is tripped, and means actuated by the keys for tripping the detent.

13. In a coin-delivery machine, coin-ejectors, means for operating the ejectors, a shaft, means for selectively establishing an actuating connection between the shaft and the ejector-operating means, keys controlling said selective connecting means, an electric motor driving the shaft, a switch controlling the motor circuit, said switch consisting of a stationary and a movable member, a pivoted support for the movable switch member, a detent for holding said support, means for swinging the support to engage its switch member with the stationary switch member when the detent is tripped, means actuated by the keys for tripping the detent, and means operated by the shaft for swinging the aforesaid support to disengage its switch member from the stationary switch member, such movement of the support re-engaging the detent therewith.

14. In a coin-delivery machine, coin-ejectors, and means for selectively operating said ejectors, said means including a rotatable shaft having actuating means which are adjustable to vary the length of the working stroke of the ejectors.

15. In a coin-delivery machine, coin-ejectors, and means for selectively operating said ejectors, said means including a rotatable shaft having wiper arms, and blades carried by said arms and adjustable lengthwise to vary the length of the working stroke of the ejectors.

16. In a coin-delivery machine, coin-ejectors, and means for selectively operating said ejectors, each of said means including a slidably supported stem, and a yieldable connection between said stem and an ejector.

17. In a coin-delivery machine, coin-ejectors, and means for selectively operating said ejectors, each of said means including a slidably supported stem, a collar loose on the stem and operatively connected to an ejector, stationary abutments on the stem between which the collar is positioned, and a spring between the collar and one of the abutments.

In testimony whereof we affix our signatures.

ROBERT CAIRNS.
JOSEPH W. CAIRNS.
